RADIO ANTENNA

Benjamin W. Blanchard, Jr., Pine Hill, N. J.

Application April 8, 1947, Serial No. 740,069

4 Claims. (Cl. 250—33)

1

My invention relates to a new and useful radio antenna and is related to my application Serial No. 266,453 while including improvements which enhance the receptive qualities of the apparatus.

An object of the invention is to provide an antenna composed of two sets of windings in bilateral relation and each set comprised of three homocentric windings, all so related to one another that the radio wave impulses broadcast from any sending station will be picked up, regardless of the impedance of the receiver, or frequencies or direction of the transmitting station.

Another object of the invention is to provide a radio antenna having unique structural features to produce a rather small and compact organization of parts which will accomplish all of the purposes desired for a device of this character and surpassing any known antenna of its kind.

Another object of the invention is to provide a radio antenna which is equally efficient on all frequencies and therefore will receive all wave lengths rather than merely quarter, half, three-quarters or other sub-divisional or proportional lengths of any full wave. In other words, the elements of the antenna are so arranged that said antenna will receive not only broadcasted short waves but will receive the longest waves employed in broadcasting radio programs rather than receiving only some fractional part of the waves which is one of the causes of poor reception.

Another object of this invention is to provide a radio antenna that has no body capacity and therefore is unaffected by a person or a pet or other animal actually coming in contact therewith or approaching the same.

Another object of the invention is to provide a radio antenna that absolutely is non-directional and therefore may be placed in any position within, on, adjacent to or remote from the radio receiving set.

Another object of the invention is to provide a radio antenna which has little or no effect of outside capacitance and therefore is practically free from static and many interfering elements.

A further object of this invention is to provide a radio antenna which has a very high degree of selectivity, increases signal strength which makes for amplification and assists in reproducing the received sound waves with fidelity.

A still further object of the present invention is to construct a radio antenna comprised of a chassis or frame having two sets of windings thereon in bilateral relation, each of said sets including several homocentric flat tubular dead end windings which provide for a continuity of reception or "pick-up," and screens which increase the magnetic flux of the radio frequency.

With the above and other objects in view this invention consists of the details of construction

2

and combination of elements hereinafter set forth and then designated by the claims.

In order that those skilled in the art to which this invention appertains may understand how to make and use the same I will describe its construction in detail, referring by numerals to the accompanying drawings forming a part hereof, in which:

Fig. 1 is a view of the chassis or frame for supporting the windings in proper relation.

Fig. 2 is a view of the chassis with the inner windings in place to plainly show their relation.

Fig. 3 is a similar view showing the inner and intermediate windings in place, the latter being partially broken away to illustrate their relations to one another.

Fig. 4 also is a similar view showing the several windings of each set in position with intermediate and outer ones partly broken away to show details of construction.

Fig. 5 is an enlarged face view of one of the screens with portions of the outer panel broken away.

Fig. 6 is a view of the antenna completely assembled and in a case which is partly broken away to illustrate their general relation.

Fig. 7 is a fragmentary sectional view of the chassis or frame to depict one manner of construction.

Fig. 8 is a sectional elevation, on an enlarged scale, of the chassis or frame, on the line 8—8 of Fig. 1.

Fig. 9 is a section on the line 9—9 of Fig. 8.

Fig. 10 is an enlarged face view of the completely assembled antenna unit with a portion broken away to illustrate a detail of construction.

Fig. 11 is a longitudinal sectional view thereof on the line 11—11 of Fig. 10.

Fig. 12 is a transverse section on the line 12—12 of Fig. 11.

Fig. 13 is an end view of the antenna unit with one of the metal rods broken out to show a connection of one screen with the rod to the rear of the broken one.

Fig. 14 is a diagrammatic view of the inner windings.

Fig. 15 also is a diagrammatic view of the intermediate windings.

Fig. 16 is a similar view of the outer windings.

Fig. 17 is an enlarged sectional detail view of one of the screens on the line 17—17 of Fig. 5, and

Fig. 18 is a perspective view of the rear of a conventional radio receiving set showing the connection between the radio antenna and the input of the set.

In carrying out my invention as herein embodied 20 represents the chassis or supporting frame including two spaced parallel side pieces 21 of any suitable non-conducting material such as, for example, wood and these are, preferably,

oblong in cross section with broad sides facing each other.

In the completed article there are two end metal rods 22 and 23, one at each end of the chassis and a transverse metal center rod 24, midway between said end rods, all having their ends projected through the side pieces 21 and held in place by appropriate means 25, Figs. 7 and 10, such as nuts screwed directly on the ends of said rods and engaging the side pieces. 10 Inside of the rods 22 and 23, with relation to the chassis, are two other metal rods 26 and 27, one adjacent to but spaced from each of said rods 22 and 23 and said rods 26 and 27 are projected into holes in the side pieces, Fig. 7.

Within the space between the side pieces near the center thereof, considered lengthwise, are two small transverse dowels 28 and 29 of non-conducting material. These dowels are of the same size and spaced to support certain windings to be presently described. Outwardly with respect to the small dowels are located one each of another pair of transversely arranged intermediate sized dowels 30 and 31. The latter dowels are of the same size as each other but larger than the small ones and spaced apart a greater distance than said small dowels. Beyond the intermediate sized dowels are located one each of still another pair of transversely large sized dowels 32 and 33. The last mentioned dowels 30 are of the same size as one another but larger than the intermediate sized ones and spaced apart a greater distance than said intermediate sized ones. Thus there are three pairs of different sized dowels so disposed that they increase in size from locations adjacent the transverse center of the chassis towards both ends thereof.

A metal rod 34 passes through all of the transverse rods and dowels in the longitudinal axis of the chassis and strips 35 and 36 of insulating material, such as fibre board, are mounted on the dowels and the center transverse rod 24, one on each side of the longitudinal axial rod 34 and parallel to the latter. The strips 35 and 45 36 have holes of suitable sizes to receive the dowels and the transverse center rod.

On the smaller dowels 28 and 29 are mounted two preformed flat tubular dead end inner windings 37 and 38 of insulation covered wire in bi-lateral relation to each other. Each inner winding is located between one of the strips 35, 36 and an adjacent side piece and one end of both of said inner windings is fixed to the transverse center rod 24 by making several turns on said rod and securing the same in place by a suitable fastening device, such as a screw. The other end of each winding is secured within itself to prevent unwinding.

On the pair of intermediate sized dowels 30 and 31 are mounted two preformed flat tubular dead end middle windings 39 and 40 also of insulation covered wire in bi-lateral relation to each other and surrounding the respective inner windings 37 and 38 homocentric thereto. One end of both of said middle windings is fixed to the transverse end rod 22 by making several turns on said rod and securing the same in place by suitable fastening device, such as a screw. The other end of each of said middle windings is secured within itself to prevent unwinding.

Like the other windings there are two preformed flat tubular dead end outer windings 41 and 42 of insulated wire mounted on the larger

5 dowels 32 and 33 in bilateral relation to each other and surrounding the respective middle windings 39 and 40 homocentric to the other and enclosed windings. One end of both of said outer windings is fixed to the other transverse end rod 23 by making several turns on said rod and securing the same in place by a suitable fastening device, such as a screw. The other end of each of said outer windings is also secured within or to itself to prevent unwinding.

In actual practice, the several dowels, rods and strips 35 and 36 are assembled and then the preformed windings are slipped over the ends of their respective dowels from opposite sides and one end of each winding fixed to the proper transverse rod, as above described. Next the side pieces are positioned over the ends of the transverse rods and drawn tightly against the ends of the dowels by the nuts 25. It will now be apparent that each succeeding pair of dowels will have a diameter as much larger than the preceding ones as the diameter, at least, of the insulated wire windings, so that the larger preformed windings may be readily and easily slipped over the smaller ones.

Screens 43 and 44 are imposed on opposite faces of the assembled windings and chassis to increase the magnetic flux of the Radio Frequency. Each screen Figs. 5 and 17, comprises a core panel 45 and two face panels 46 and 47 with layers of metal screenings 48 interposed between adjacent panels. The layers of screening may be separate sheets or one sheet large enough to be folded over the edge of the core panel for engagement with both faces of the latter. The panels preferably have holes 49 therethrough and all of the elements of the screen are secured together by suitable fastening devices 50, such as rivets.

The screening has two taps or leads 51 and 52 projecting therefrom, one at each end, and are connected thereto so as to be in contact with both layers of the screening as though an integral part thereof. The tap 51 of one screen, for example screen 43, is fixed to the inner transverse rod 26 adjacent one end of the device while the tap 52 of the same screen is fixed to an outer transverse rod 23 at the opposite end of the device, and the tap 51 of the other screen, as screen 44, is fixed to the inner transverse rod 27 while the other tap of said other screen is fixed to the outer transverse rod 22. In other words the taps of each screen are attached to inner and outer transverse rods at opposite ends, respectively, of the chassis.

A lead 53 for connection with the radio input side of a radio receiving set is attached to one end of the metallic skeleton framework and, preferably, to an end of the longitudinal axial rod 34 while a second lead 54, if desired, is provided for connection to an appropriate ground element. Such second lead may be attached to outer transverse rod adjacent the location of the lead 53, which rod as herein depicted is the one designated by the numeral 23.

The antenna structure described above may be enclosed in a case or box 55 of any desired or preferred material, in which circumstance the lead 53 is fixed to binding post 56 and the lead 54 is fixed to a second binding post 57, both carried by the case or box and positioned in any desirable or appropriate location, as at one end of said case or box.

In use, the antenna may be placed in any position, on an end, side or broad face either

within or outside of the receiving set and when outside of the set, either adjacent thereto or remote therefrom. This is possible because the device is non-directional and capable of picking up all radio wave lengths or frequencies. It is equally efficient when used in connection with FM and television reception. For purposes of illustration only, the antenna is shown as resting on top of a receiving set 57 in Fig. 18 with a lead 53a, which is a continuation of the lead 53, attached to binding post 56 of the antenna and the aerial or radio input side of the receiving set represented by the binding post 58. The binding post 59 represents means for connection of the receiving set with a source of electric current.

The antenna herein described is for a purpose similar to that claimed in the patents to Jones, No. 1,840,780; Speaker, No. 1,828,910; Arias 1,820,643; and Graves, 2,039,988, but dissimilar from them in construction and design and by actual comparative tests and experiments by technically qualified Radio Engineers has been found to greatly surpass the performance of the above mentioned antennae of Jones, Speaker, Arias and Graves.

It also has been discovered that distance, clarity, and fidelity are the superior and outstanding results of the invention.

Of course I do not wish to be limited to the exact details of construction herein shown and described as these may be varied within the scope of the appended claims without departing from the spirit of my invention.

Having described the invention what I claim as new and useful is:

1. A radio antenna comprising several homocentric flattened tubular dead end windings of different sizes telescoped within one another, one side of each winding connected to a lead for attachment to a receiving set, and screens disposed on opposite sides of the assembly of windings and connected to said lead, wherein the screens are each composed of a core and face panels of insulation material with layers of metallic screening between adjacent panels.

2. A radio antenna comprising several homocentric flattened tubular dead end windings of different sizes telescoped within one another, one side of each winding connected to a lead for attachment to a receiving set, and screens disposed on opposite sides of the assembly of windings and connected to said lead, wherein the screens are each composed of a plurality of spaced parallel apertured panels of insulating material, layers of metallic screening disposed between adjacent panels, and means to secure said panels and layers of screening together in a unitary structure.

3. A radio antenna comprising duplicate sets of several flattened tubular dead end windings telescoped within one another, a transverse metallic rod extending through the innermost and smallest winding to which one end of each of said smallest windings is connected, second and third transverse metallic rods outside of the sets of windings, one at each end of said sets of windings, an end of each of the intermediate windings connected to one of said end rods and an end of each of the outer windings connected to the other of said end rods, and a longitudinal axial rod connected to the transverse rods and providing part of a lead for connection to the radio input side of a receiving set, in combination with screens disposed at opposite broad

sides of the sets of windings and extending completely over the entire area of said sets of windings, each screen consisting of alternative layers of metallic screening and panels of insulating material with panels outside, taps connected with all layers of the screening at opposite ends thereof, one tap of each screen connected to one of the outer transverse rods at opposite ends of the assembly, and other transverse rods outside of the windings and inside of the end rods and to which the other taps are connected at opposite ends.

4. A radio antenna comprising, in combination, a chassis consisting of longitudinal axial metal rod, a center transverse metal rod mounted on said axial rod, three pairs of different sized transverse dowels, the dowels of each pair being of the same size, said dowels mounted on the axial rod with one of each pair on each side of the center transverse rod with the smaller ones adjacent said center transverse rod and the larger ones furthest removed from said center transverse rod, transverse metal outer end rods mounted on the axial rod at the ends thereof, transverse metal inner end rods also mounted on the axial rod adjacent to but spaced from the outer end rods, strips of insulating material mounted on the dowels at both sides of the axial rod, and side pieces connected with all of the transverse rods and secured to a number of said transverse rods and engaging the ends of the dowels, two sets of three pre-formed dead end windings of different sizes telescopically mounted relative to one another on their respective dowels, the sets being in bilateral relation, one end of each inner and smallest winding connected to the transverse center rod and one end of each outer and intermediate winding connected to opposite transverse outer end rods, said windings being assembled prior to the mounting of the side pieces, screens disposed on opposite sides of the windings, each screen comprising apertured core and face panels in spaced parallel relation and layers of metallic screening disposed between adjacent panels with means to fasten the parts together in a unitary structure and taps at opposite ends of the screen, the taps being connected to an inner and outer end rod at opposite ends of the chassis and the taps of one screen being in opposed relation to those of the other screen, and a lead connected with one end of the axial rod adapted to be attached to the radio input of a receiving set, in combination with a case having binding posts and in which the antenna is completely enclosed with the lead connected to one of said binding posts, and a ground lead connected with one of the outer end rods and the other binding post.

BENJAMIN W. BLANCHARD, JR.
